UNITED STATES PATENT OFFICE

JAMES D. HASKINS, OF BROOKLYN, NEW YORK

DESIGN FOR A DISPLAY STAND

Application filed June 9, 1931. Serial No. 40,136. Term of patent 3½ years.

To all whom it may concern:

Be it known that I, JAMES D. HASKINS, a citizen of the United States, residing at Brooklyn, in the county of Kings, State of New York, have invented a new, original, and ornamental Design for a Display Stand, of which the following is a specification, reference being had to the accompanying drawing, forming part thereof.

In the drawing:

The figure is a front elevation of the display stand showing my new design comprising a plurality of hands all of the same thickness.

I claim:

The ornamental design for a display stand, as shown and described.

JAMES D. HASKINS.
